UNITED STATES PATENT OFFICE.

DAVID H. FREEMAN, OF BRAZIL, TENNESSEE.

CAR-CO尤LING APPARATUS.

SPECIFICATION forming part of Letters Patent No. 403,341, dated May 14, 1889.

Application filed February 5, 1889. Serial No. 298,741. (No model.)

To all whom it may concern:

Be it known that I, DAVID H. FREEMAN, of Brazil, in the county of Gibson and State of Tennessee, have invented certain new and useful Improvements in Apparatus for Coupling and Uncoupling Cars; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in automatic car couplers and uncouplers.

The object of my invention is to provide an improved car-coupler simple, cheap, and durable in construction and composed of a minimum number of strongly-constructed parts, and which will automatically couple when the cars come together; and a further object is to provide means by which the cars or any car can be automatically uncoupled from the rest of the train while in motion from the side of the track without any danger or risk to the operator; and the mechanism is so constructed that the cars will not be uncoupled until the particular car to be detached reaches the uncoupling-point. These objects are accomplished by and my invention consists in certain novel features of construction and combinations of parts more fully described hereinafter, and particularly pointed out in the claims.

Referring to the accompanying drawings, Figure 1 is a top plan of the adjoining ends of two cars and the track, showing the uncoupling mechanism on the track. Fig. 2 is a side elevation of the same. Fig. 3 is a perspective detail view of the coupling-heads locked and the uncoupling mechanism located upon either side of the track. Figs. 4 and 5 are detail elevations of the coupling-heads. Fig. 6 is an elevation of the hinged uncoupling post or lever located upon the track. Fig. 7 is a detail view of the pivoted lever loosely secured to one of the coupling-heads and adapted to engage one of the uncoupling-posts.

In the drawings, the reference-letter *a* indicates a railroad-track, and *b* the cars upon the same.

The coupler consists of the coupling-heads *c* *d*, provided with the usual draw-bars, *e*, secured to the ends of the car to yieldingly give to longitudinal strain. One of these draw-bars is pivoted to the car to allow lateral swing of the head *d*, carried by the same, which is of the form of a horizontal hook open on one side to swing laterally into or from engagement with the other head, *c*, which is constructed in the form of a vertical open frame upon the end of the draw-bar, provided with the vertical end bar, *g*, with which the hook of the opposite head engages when the coupling is effected. This bar *g* is preferably constructed longer than the thickness of the hook, (see Fig. 2,) so that the coupling can be used where the cars vary in height. The hook coupling-head *d* is yieldingly held to the limit of its lateral movement in one direction by a spring, *h*, as shown.

It will be seen that when the cars come together the beveled front end of the hook will engage the vertical bar *g* of the open frame of the opposite head, which will throw the hook laterally against the pressure of the spring to pass the bar, and when its front end has passed the bar the spring will force the hook into engagement with the same, and thereby yieldingly hold the parts locked together.

A rigid vertical post, *h'*, is located upon one side of the railway-track. Upon the other side of the track, opposite the post *h'*, a hinged post or lever, *i*, is located, and this post at its lower end is suitably hinged to allow its free end to swing in a vertical plane from a vertical position beside the track away from the same, and the upper end of this hinged post *i* is provided with a block or cam, *j*, the inner face of which parallel with the track is preferably, although not necessarily, beveled or inclined from the center of the block toward the ends, as shown.

A rod, *K*, is secured to and extends laterally from the side of the hook-head opposite to that upon which the spring bears, and this rod is of such length that it will engage the block *j* when the hinged post carrying the same is swung into vertical position. This arm or rod is supported to allow longitudinal movement of the same by suitable brackets secured to the end of the car. (See Fig. 1.)

A rigid arm, *l*, projects forwardly from the opposite end of the car and upon the opposite side of the coupling, and upon this arm a lever, *m*, is pivoted in a suitable manner, as 5 by a pin projecting up through a longitudinal slot, *n*, in the lever. The inner end of this lever is provided with a yoke, *o*, loosely embracing the draw-bar of the coupling-head *c*, and adapted, when the coupling is effected, 10 to slide up upon the coupling-head and partially close the opening in the same, (see Fig. 2,) and thereby prevent the hook from becoming accidentally disengaged from the bar *g*.

The opposite end of the lever *m* is adapted 15 to engage the rigid post *h*, located beside the track.

The operation is as follows: Suppose the cars to be coupled and approaching the uncoupling-point. If it is desired to detach one 20 of the cars from the train, the operator or switchman will swing back the hinged post until the cars preceding the one to be detached have passed. The post will then be swung into the vertical position shown in Fig. 25 3, so that the rod *k* can engage the same; but just before this rod strikes the hinged post the lever *m* strikes the post *h*, and is thereby swung, and throws back the yoke *o* from the coupling-head, so that the hook can be 30 disengaged. The free end of the rod *k* will then come in contact with one end of the block upon the hinged post, and as it passes along its inclined face the rod will be forced longitudinally and throw the hook laterally 35 against the pressure of the spring from the bar *g* of the opposite head, and thereby uncouple the cars. If desired, the rod *k* can be provided with a notch, *p*, to engage one of the supporting-brackets and removably hold the 40 hook in its uncoupled position.

The front face of the block on the hinged post is provided with a friction-roller, *q*, which will force down the end of the rod *k* as it passes along the face of the block, and thereby 45 throw the notch *p* into engagement with the bracket. The end of the rod or arm *k* is preferably provided with an anti-friction roller on its end to engage the uncoupling-post or other device located beside the track and 50 adapted for the same purpose as the post *z*.

From the foregoing description and the drawings the great simplicity and strength and durability of the construction are obvious, and it will be observed that the cars are 55 both coupled and uncoupled automatically, and, if desired, the coupling-heads can be provided with the usual rods or levers, so that the coupling can be operated from the cars. It is also evident that various changes might 60 be made in the form and arrangement of the parts described without departing from the spirit and scope of my invention; hence I do

not wish to limit myself to the precise construction herein set forth; but

What I do claim is—

1. A car-coupling head provided with an uncoupling rod or arm extending laterally from the same beyond the side of the car and adapted to engage and be moved by a post located beside the track, and thereby release the coupling-head from the opposite coupling member, substantially as described. 65 70

2. A car-coupling comprising two coupling-heads, a movable yoke to detachably hold the heads coupled, a lever connected to the yoke 75 and extending beyond the side of the car, and adapted to engage a post located beside the track and move the yoke to allow the separation of the heads, and a rod or arm extending from one of the heads and adapted to engage and be moved by a post located beside the track, and thereby unlock the heads, substantially as described. 80

3. An automatic car-coupling comprising a coupling-head consisting of a laterally-swinging hook to engage the opposite coupling member, and a longitudinally-movable rod to swing the hook laterally to uncouple the same and adapted to engage and be operated by a post located beside the track and when the car is 90 moving, as set forth. 85

4. An automatic car-coupling comprising one coupling member consisting of a draw-bar having an open frame or head on its end provided with an end bar, the other member consisting of a hook to engage said bar, and a yoke movable on the draw-bar and adapted to partially close the opening in the head and hold the hook therein, substantially as described. 95 100

5. An automatic car-coupling, a coupling member consisting of an open frame or head upon the end of a draw-bar, a yoke movable on the draw-bar and adapted to partially embrace the open head, and a lever pivoted to an arm of the car to operate the yoke and 105 extending beyond the side of the car and adapted to engage a post and be operated thereby, substantially as described. 110

6. Means to automatically uncouple rail-way-cars, comprising a post hinged at its lower end beside a railroad-track to swing from a vertical position backwardly from the track and provided with a block having inclined faces on its side toward the track, adapted to be engaged by and move longitudinally a rod connected with and adapted to uncouple passing cars, substantially as described. 115

In testimony that I claim the foregoing as my own I affix my signature in presence of two witnesses.

DAVID H. FREEMAN.
